UNITED STATES PATENT OFFICE.

SETH H. LEAVENWORTH, OF CINCINNATI, OHIO, ASSIGNOR TO THE HOMAN
SILVER PLATE COMPANY, OF SAME PLACE.

DESIGN FOR A HOME-ALTAR.

SPECIFICATION forming part of Design No. 83,115, dated August 21, 1900.

Application filed July 23, 1900. Serial No. 24,612. Term of patent 7 years.

To all whom it may concern:

Be it known that I, SETH H. LEAVENWORTH, a citizen of the United States of America, and a resident of Cincinnati, in the county of Hamilton and State of Ohio, have invented and produced a certain new and original Design for Home-Altars, of which the following is a specification.

Figure 1 is a front elevation of a home-altar embodying my invention. Fig. 2 is a side elevation of the same.

The principal features of my design are the pedestal A and the canopy B. The front of the pedestal has at the sides upright posts $a a'$, which terminate at both ends in clusters a^2 . From the upper end of the posts arcs a^3 extend to the floor a^4 of the pedestal, forming, with the post, spandrels which contain foliated decorations. Below the floor is a Gothic arch the space between which and the floor is filled in with decorations of a character similar to that of the spandrels. Brackets a^5 have projecting from them arms a^6 in the form of leaf and flower bearing branches, which terminate in candle-holders a^7 in the form of a corolla.

The canopy consists of angles $b b'$, surmounted by crockets b^2 in the form of curved leaf-bearing branches and terminated at its apex in a finial b^3 , bearing a Latin cross. At 30 the lower ends of the angles are pendants b^4 b^5 , extending down at points above posts $a a'$ and terminating at a distance above the posts in clusters similar to those at the ends of the posts. The lower edge of the canopy 35 is in the form of a Gothic arch, and the space between the arch and the angles is filled in with foliated decorations.

Each side of the altar has a large oval perforation in it above the line of the floor. 40 Upon the edge of these perforations opposite the spaces between the posts and the pendants of the front are foliated strips C C'.

What I claim is—

The design for a home-altar substantially 45 as shown and described.

SETH H. LEAVENWORTH.
